United States Patent

Des. 234,663
Patented Apr. 1, 1975

234,663

OPEN FILE

Frank Joseph Stiene, Ridgewood, N.J., assignor to
Mercedes-Benz of North America, Inc., Montvale, N.J.

Filed Aug. 21, 1972, Ser. No. 282,577

Term of patent 14 years

Int. Cl. D6—04

U.S. Cl. D6—181

FIG.1

FIG.2

FIG.3

FIG.5

FIG.6

FIG.4

FIG. 1 is an oblique perspective view from in front and above, of an open file embodying my novel design;

FIG. 2 is a front view of the open file of FIG. 1;

FIG. 3 is a rear view of the open file of FIG. 1;

FIG. 4 is a side view of the open file of FIG. 1;

FIG. 5 is a top view of the open file of FIG. 1; and

FIG. 6 is a bottom view of the open file of FIG. 1.

I claim:

The ornamental design for an open file, as shown and described.
